CLAIM

The ornamental design for a shoe upper, as shown and described.

DESCRIPTION

FIG. 1 is a front perspective view of a shoe upper showing a first embodiment of my new design;

FIG. 2 is a side view thereof;

FIG. 3 is a top view thereof;

FIG. 4 is a rear perspective view thereof;

FIG. 5 is a front perspective view of a shoe upper showing a second embodiment of my new design;

FIG. 6 is a side view thereof;

FIG. 7 is a top view thereof; and,

FIG. 8 is a rear perspective view thereof.

The broken lines immediately adjacent to the shaded area define the bounds of the claimed design and form no part thereof. In each embodiment, the six unshaded eyelet regions within the shaded area that are demarcated by broken lines form no part of the claimed design. The broken lines showing of the remainder of the shoe are for environmental purposes only and form no part of the claimed design.
